(57) **CLAIM**

The ornamental design for a grass trimmer, as shown and described.

DESCRIPTION

FIG. 1 is a perspective view of a grass trimmer of the present invention;

FIG. 2 is a front view of the grass trimmer of FIG. 1;
FIG. 3 is a rear view of the grass trimmer of FIG. 1;

FIG. 4 is a right side view of the grass trimmer of FIG. 1;

FIG. 5 is a left side view of the grass trimmer of FIG. 1;

FIG. 6 is a top view of the grass trimmer of FIG. 1; and,

FIG. 7 is a bottom view of the grass trimmer of FIG. 1.

Any broken lines in FIGS. 1-7 form no part of the claimed design.

1 Claim, 7 Drawing Sheets# US D1,105,868 S
